SCAFFOLD

Filed Nov. 26 1923

24 Inventor
Nick Timmons,

Attorney

Patented Mar. 24, 1925.

1,531,159

UNITED STATES PATENT OFFICE.

NICK TIMMONS, OF HUNTSVILLE, ALABAMA.

SCAFFOLD.

Application filed November 26, 1923. Serial No. 677,073.

To all whom it may concern:

Be it known that I, NICK TIMMONS, a citizen of the United States, residing at Huntsville, in the county of Madison and State of Alabama, have invented new and useful Improvements in Scaffolds, of which the following is a specification.

The scaffolding forming the subject matter of the present application for patent has been designed more particularly for use by window cleaners to facilitate working upon windows from the outside. The invention is capable of employment whenever work is required to be done from the outside of a window, whether it be painting, repairing, or the like.

Primarily, the invention contemplates the provision of a novel and improved scaffold which can be readily put in place and removed, and which obviates the necessity of using nails or other fasteners which would mar the window frame or the sill.

As a further object, the invention aims to furnish a scaffold of the character indicated which will be adjustable to various dimensions thus rendering it applicable to windows of different sizes.

A further object of the invention is the provision of a scaffold of this kind wherein an improved collapsible railing is provided as a guard against the occupant falling therefrom.

A still further object of the invention is to provide a scaffold of this kind which will be very simple in construction, highly efficient and convenient in use, and which may be inexpensively manufactured and sold.

The various features of novelty which characterize my invention are pointed out with particularity in the claim annexed to and forming a part of this specification. However, for a better understanding of the invention, and of the advantages possessed by it, reference should be had to the accompanying drawing and descriptive matter in which I have illustrated and described what I now regard as the preferred embodiment of my invention.

In the drawing,

Figure 1 is a longitudinal sectional view of a scaffold embodying my invention, the same being shown applied to a window;

Fig. 2 is a cross-section of a window frame, showing a fragment of my scaffold in plan, and

Fig. 3 is a perspective view of my scaffold, a portion of the railing being broken away.

Referring specifically to the drawing, wherein like reference characters have been used to designate like parts throughout all views, numeral 4 denotes a window frame generally, to which my scaffolding is applied. The scaffold is provided with two extensible side members having overlapping rails 5 and 6. Straps 7 extend about the rails 5 and 6 and permit the same to partake of longitudinal movement with respect to each other during the adjustment of the scaffold. Fig. 3 plainly illustrates that screw bolts 8 may be carried by the straps 7 and are provided with winged heads by means of which the screw bolts may be conveniently turned for tightening or loosening the same. These two extensible frame members embodying the rails 5 and 6 are connected for lateral adjustment by means of two extensible members, one of which comprises rails 10, the inner ends of which carry metal straps 11 for guiding the sliding movement and further for limiting such movement. This construction is best illustrated in Fig. 3. The other element for permitting lateral adjustment of the scaffolding frame embodies means for associating the scaffold with the window frame and will be referred to presently.

The longitudinally extensible frame members 6 are provided at diametrically opposite points with straps 13 for the reception of legs 12, it being evident that these legs will be slidable in the straps and that they will be held in a predetermined adjusted position by means of the clamping nuts 14. The purpose of these legs 12 is to support the scaffold, the legs being adapted to rest upon the window ledge 15 as clearly shown in Fig. 1.

The second means for directing or guiding the lateral adjustment of the extensible longitudinal frame members embodying the rails 5 and 6 has been referred to incidentally hereinabove, and constitutes extensible rails 16 which carry at their ends metal straps 16^a whereby the rails will be held in proper position. Each of these rails 16 is connected near its outer end to the end of one of the members 5, the connection being had by means of a threaded shank extending through said rail 16 and adapted to receive a clamping nut 17. Other attaching

means may be employed where expedient, and it will be noted that I have provided wing nuts for facilitating knocking down of the scaffolding when it is to be shipped or stored. The ends of the extensible members 16 are provided with hooks 18 which are adapted to grip the outer edge of the inside window frame as clearly shown in Fig. 2, wherein the portion of the window frame 10 aforementioned is indicated at 19.

From the foregoing description read in connection with the accompanying drawing, the application of the scaffolding to a window frame will be evident. As the first step, 15 the legs 12 will be adjusted to rest upon the ledge 15 so as to position the side members embodying the extensible rails 5 and 6 in horizontal position. The hooked ends of the members 16 will now be engaged with the 20 portion of the window frame as at 19. This construction will form a fairly stable scaffold if the extended portion of the same is to support a light weight. However, I have provided a further supporting expedient for 25 the extended portion of the scaffold, and the same embodies a pair of rods 20 which are pivotally carried by blocks 21 which are slidable in slots 22 in the outer ends of the rails 6 as clearly shown in Fig. 3, the blocks 21 being secured in the slots by means of wing nuts 23. The purpose of this slotted connection will become presently apparent. The other ends of the supporting rods 20 are provided with hooks denoted at 20^a which 30 are adapted to engage with eyes 24^a of a rod 24 which extends vertically upward and is provided with a medial offset 24^b for clearing the outer edge of the window ledge 15 as shown in Fig. 1. The connection of the rod 24 with the outer sides of the rails 5 is 35 a pivotal connection as indicated at 24^c. The supporting rods 24 rest against the building wall 25 which is made to take up the strain of weight upon the scaffold, the members 20 acting as props.

It is proper here to again emphasize the knock down construction of the scaffold, every member of which can be readily disassociated from its co-operating element 40 when desired.

The rails 5 and 6 constitute the support for the flooring or platform 33, the same being held in place by means of suitable clips or clamps 34, the specific character of which is immaterial to the present invention. In order to render the scaffold safer, I have provided a railing therefor, which embodies upright members 26 which are pivoted to the outer ends of the rails 6 and are in turn 45 pivotally connected at their upper ends to longitudinally disposed horizontal rails 28,

the other ends of which are connected as at 50 to upright supports 27 which latter in turn are pivoted at the outer side of the rails 5 as clearly shown in Fig. 3. A horizontal 65 rail is provided between the members 26 and constitutes extensible portions 30 which are slotted as indicated at 31 to allow for lateral adjustment of the scaffold frame as hereinbefore referred to. A clamping element 32 70 serves to hold this member in adjusted position. From the foregoing, it will be apparent that the railing of the scaffold will be pivotally secured to the extensible sides thereof and may be folded down upon the 75 frame. However, in order to maintain the structure in upright position, I have provided sectional braces denoted generally at 80 35 which are pivotally connected to the members 27 and 28 and also intermediate 85 their ends whereby movement of the railing will be prevented except when the hinged joint of said sectional brace is broken.

The slotted connection between the supporting members or props 20 and the rails 6 85 is for the purpose of adjusting the props toward and from the window in accordance with the extended relation of the members 5 and 6. It will be obvious that when the side portions of the scaffold are extended by 90 projecting the rails 6 outwardly that in order to secure a proper support for the extended portions thereof, the props or supporting members 20 will have to be pulled inwardly toward the window sill.

While I have described and illustrated the preferred embodiment of my invention, as heretofore stated, yet it will be understood that various changes and modifications may be made therein without departing from the 100 spirit of my invention as defined by the following claim.

Having thus described my invention, what I claim as new and desire to secure by Letters Patent is:—

A window scaffold comprising a pair of extensible side members adapted to extend through a window frame, an extensible end member connected to the extensible side members and having its ends provided with lugs to engage the outer vertical edges of the inner side of a window frame, legs adjustably carried by said extensible side members, triangular braces connected to said extensible side members and having upstanding members to flatly contact with the outer surface of a wall, said braces also being provided with inclined members having pivotal connection with said upstanding members.

In testimony whereof I affix my signature.

NICK TIMMONS.
